UNITED STATES PATENT OFFICE.

DORSEY W. ALMOND, OF LEADVILLE, COLORADO.

COMBINED ORE CONCENTRATOR AND AMALGAMATOR.

SPECIFICATION forming part of Letters Patent No. 739,971, dated September 29, 1903.

Application filed November 8, 1902. Serial No. 130,588. (No model.)

To all whom it may concern:

Be it known that I, DORSEY W. ALMOND, a citizen of the United States, residing at Leadville, in the county of Lake and State of Colorado, have invented new and useful Improvements in a Combined Ore Concentrator and Amalgamator, of which the following is a specification.

My invention relates to improvements in ore-concentrators; and it consists in the peculiar and advantageous combined ore concentrator and amalgamator hereinafter described, and particularly pointed out in the claim appended.

15 In the accompanying drawings, Figure 1 is a diametrical section of a combined ore concentrator and amalgamator constituting the preferred embodiment of my invention, and Fig. 2 a plan view of the same with the drive-shaft in section.

Similar letters of reference designate corresponding parts in both views of the drawings, referring to which—

20 A is the bed or support of my improved apparatus, which may be of any suitable description; B, a stationary pan, preferably circular in form, arranged on the bed; C, a discharge conduit or launder leading from the bottom of the pan; D, an annular downwardly and inwardly pitched or inclined wall arranged on the side wall *a* of pan B and having the upwardly-extending wall *b* at its outer edge. The portion of the apparatus thus far described is stationary, and the walls 25 *D b* thereof are either formed of or faced, as indicated by E, with copper which has been amalgamated.

25 F is a fixed central bearing, which preferably extends upwardly through the conduit C and pan B, and G a shaft stepped in the bearing F and having for its purpose to bear the rotary portion of the apparatus. The shaft G is shown as equipped at its upper end with a miter-gear *c*, intermeshed with a miter-gear *d* on another shaft *e*; but it is obvious that motion may be transmitted to said shaft G in any other approved manner without departing from the scope of my invention.

30 The rotary portion of the apparatus preferably comprises a receptacle *f*, surrounding the shaft G and fixed at its bottom thereto, a plurality of pipes *g*, communicating with and

extending radially from the receptacle and arranged to discharge downwardly on the amalgamated-copper facing E of the walls 35 *D b*, and a downwardly and inwardly pitched or inclined wall *h*, surrounding and connected to the upper end of the receptacle and having a marginal wall *i*. The walls *h i* are designed to be formed of or faced, as indicated 40 by H, with copper which has been amalgamated.

45 I is a conduit or launder through which finely-commинuted ore or pulp and water are supplied to the apparatus, the said conduit 45 being arranged, as shown, to discharge on the copper-faced wall *h*.

50 In the practice of my invention when the shaft G is rotated, and pulp and water are supplied to the apparatus through the conduit I the pulp and water will pass over the copper plate H, through the receptacle *f* and distributing-conduits *g*, and over the copper plate E to the pan B. Incident to such passage of the pulp and water through the apparatus a portion of the gold and silver contained in the ore will be caught and retained by the plate H, while the remainder thereof will be held by the plate E. The plate H by reason of its inclination enables the wet pulp 55 to slip or wash down into the receptacle *f*, and the inclined plate E performs a like function with reference to the pan B. Incident to the operation the heavier particles of pulp will remain where they fall in the pan B, while the 60 lighter particles—viz., tailings and slimes—will wash over the heavy particles and be discharged through the conduit C.

65 It will be appreciated from the foregoing that notwithstanding the simplicity of my improved ore concentrator and amalgamator the same is highly efficient in operation and requires but a minimum amount of attention; also, that the construction is such that the apparatus may be "cleaned up"—i. e., the collected gold and silver may be removed—with great facility.

70 While I prefer to employ copper which has been amalgamated for the purpose of catching and retaining the gold and silver present in the pulp, I do not desire to be understood as confining myself to the same, as the rotary tray and the stationary pan or receptacle may be otherwise equipped to perform that func-

tion without departing from the scope of my invention. I also do not desire to be understood as confining myself to the specific construction and relative arrangement of parts 5 embraced in the present and preferred embodiment of my invention, as such changes or modifications may be made in practice as fairly fall within the scope of my claim.

The copper facings or plates E and II are 10 amalgamated with mercury or quicksilver or its equivalent, and the amalgamation may be and preferably is effected in the conventional manner.

I generally prefer to provide the pipes g 15 with sweeps g', of canvas or other suitable textile material. These sweeps are designed to remove the sand and waste particles from the ore with a view of accelerating the concentration.

20 Having described my invention, what I claim, and desire to secure by Letters Patent, is—

The herein-described combined ore concentrator and amalgamator consisting essentially 25 of a bed or support, a stationary receptacle arranged thereon, and made up of a pan, an annular, downwardly and inwardly inclined wall D mounted on the upper edge of the side wall of and arranged to discharge into the 30 pan, and equipped with means for catching

and holding gold and silver, a wall b extending upwardly from the outer edge of said wall D, and a discharge-conduit leading from the center of the bottom of the pan, a fixed bearing F extending through said conduit and the bottom of the pan, a vertical-shaft journaled in said bearing, a rotary tray fixed on the shaft, above the center of the pan, and comprising a receptacle, an annular downwardly and inwardly inclined wall h mounted on the upper edge of the side wall of and arranged to discharge into the receptacle, and equipped with means for catching and holding gold and silver, and a wall i extending upwardly from the outer edge of the wall h, radial pipes connected to the receptacle of the tray, and arranged to discharge on the wall D of the stationary receptacle, means for supplying pulp and water to the inclined wall of the tray, and sweeps connected to and carried by the radial pipes, and movable in the stationary receptacle.

40 In testimony whereof I have hereunto set my hand in presence of two subscribing witnesses.

DORSEY W. ALMOND.
